UNITED STATES PATENT OFFICE.

FRANCIS M. CASE, OF CLEVELAND, OHIO, ASSIGNOR TO FEDERAL PORCELAIN COMPANY, OF CAREY, OHIO, A CORPORATION OF OHIO.

NAIL-KNOB ASSEMBLING AND SECURING MACHINE.

Application filed October 14, 1922. Serial No. 594,530.

My invention relates to a machine for preparing nail knobs and particularly to a machine wherein a pair of opposed porcelain knobs are mounted on a nail with or without holding or protecting washers. It has been customary in the past to secure the knobs permanently on the nail by crimping or otherwise enlarging the stem of the nail. I provide an attachment for nail knob machines whereby the crimping may, if desired, be eliminated; the knobs being held in position on the nail by a metal washer which is driven upon the nail and is clamped closely thereupon. My purpose is to provide means for feeding such a washer to a nail engaging punch and for providing the necessary punch and the means for using it. Another object is to provide unit means for feeding the washers and for operating the punch. Other objects will appear from time to time in the course of the specification.

I illustrate my invention more or less diagrammatically in the following drawings, wherein:

Figure 1 is a plan view of the nail knob assembly machine, with my invention applied thereto with parts removed.

Figure 2 is an enlarged plan view with parts in outline, showing the upper right hand part of Figure 1;

Figure 3 is a vertical section on the line 3—3 of Figure 2;

Figure 4 is a section on the line 4—4 of Figures 3 and 6;

Figure 5 is a section on the line 5—5 of Figure 4;

Figure 6 is an enlarged detail of the washer feed slot and feed control;

Figure 7 is a finished nail knob assembly;

Figure 8 is a detail section on the line 8—8 of Figure 1 with punch in upper position.

Figure 9 is a section on the same line as Figure 8 but showing parts lying below on a larger scale.

Figure 10 is a detail section of the upper end of the punch showing the washer forced up on the nail.

Figure 11 is a section on the line 11—11 of Figure 9.

Figure 12 is a section on the line 12—12 of Figure 8.

Figure 13 is a side elevation of the hopper with parts broken out and the hopper blade in upper position.

Figure 14 is a section on the line 14—14 of Figures 12 and 13.

Figure 15 is a plan view of the parts shown in Figure 13 with the hopper blade in the lower position.

Like parts are indicated by like symbols throughout the drawings.

A is a machine bed preferably formed of a single casting which may be supported on any suitable framework not herein shown in detail. It is channeled at A¹ adjacent the front of the machine, and within the channel A¹ is any suitable conveyor belt A² upon which the pairs of axially perforated nail knobs may be placed for conveyance inwardly from the edge of the machine. The pairs of porcelain blanks are carried forward into the notches A³ of the circular rotating carrier table A⁴ which is given an intermittent rotation by any suitable means not herein shown in order to carry the nail knob pairs forward by a step by step rotation.

At the position marked "X", each pair of nail knobs halts during this step by step motion and the nail is passed therethrough. If desired, a washer may be fed above the knobs and beneath the nail which then transfixes the washer before penetrating the knobs.

When the nail knob pair reaches the position marked "Y" in Figure 1, a second washer is fed beneath the assembly and the nail is driven down through it. At the position marked "Z" the stem of the nail beneath the nail knobs and washers may be suitably enlarged, crimped, or deformed to prevent the removal of knobs and washers from the nail.

The various washer feeds and the crimping step any and all of them may be eliminated, particularly the latter and instead the mechanism below described may be used to feed and affix a metal washer in frictional or crimping engagement with the stem of the nail.

B is any suitable drive shaft driven from any suitable power source having mounted on it the gear B¹ which drives the gear B²

rotating on the shaft B³. Mounted to rotate with the gear B² is the cam element C which is provided with a spiral cam surface C¹ and an inwardly inclined surface C² terminating in a plurality of scallops C³.

Pivoted to C as at D is the link D¹ pivoted as at D² to hopper blade D³ which is adapted to be oscillated in a vertical slot opening into the bottom of the hopper D⁴. This 10 hopper comprises in part opposed inclined converging sections, D⁷, D⁸ and is provided with an outward extension D⁹ to the outer ram's horn end of which is pivoted the hopper blade lever D¹⁰. The hopper is mounted on the upper ends of a plurality of vertical rods, D¹², the lower ends of which are secured in any suitable fashion to the upper surface of the machine as at D¹⁴. The top 15 of the machine is apertured as at D¹⁵ to permit the passage of the link D¹. The hopper blade is provided with an upper slot D⁵ which is adapted to pick up the thin perforated metal washers with which the hopper is kept filled. As it rises, these washers 20 ride forward in the slot and are dropped into the upper end of the washer chute E and dropped down it to the inclined portion E¹. D⁶ are agitating and collecting wires which tend to drop washers into the slot. 25 The lower portion of the chute E¹ is formed of two opposed spaced plates E², E³ secured by the screws E⁴. The blade D³ is slotted to receive the tongue D²⁰ which serves to hold the groove D⁵ in the top edge of the 30 blade D³ in accurate alignment with the entrance to the chute E.

K²⁰ is a kick-out lever adapted to penetrate the top portion of the chute E. It is keyed upon any suitable rotatable sleeve or 40 shaft K²¹ mounted upon the top of the hopper D⁴. At the opposite end of this shaft sleeve is keyed a slotted lever link K³ having a slot K⁴ adapted to be penetrated by a pin K⁵ upon the end of the vertical rod K⁶. 45 The rod is mounted for axial movement in the sleeve K⁷ secured to the hopper D⁴. The rods extend beneath the lower edge of the sleeve and is provided with a stop K⁸ between which and the end of the sleeve is 50 compressed the spiral spring K⁹. The lower end of this rod is adapted to be contracted by an adjustable set screw K¹⁰ mounted upon the hopper blade lever D¹⁰. It will be understood that as the hopper blade is raised 55 and lowered through the hopper the kick-out is alternately lifted from the top of the chute and allowed to kick back into it in response to the action of the spring K⁹ drawing down upon the rod K⁶.

60 Pivoted as at F beneath the chute section E¹ is the U-shaped yoke F¹ slidably mounted on each extremity of which are the pins F², F³, each kept yieldingly in place by the spring F⁴ which press against the heads F⁵, F⁶. These pins are spaced in relation to the

chute as shown in Figure 6, and are adapted to penetrate the chute at a distance apart substantially equal to the diameter of one washer.

One arm of the yoke is upwardly continued, and has integral with it a perforated screw threaded boss F⁷ penetrated by a stop screw F⁸ provided with a lock nut F⁹. The spring F¹⁰ is compressed between the boss F⁷ and the plate E³, and tends to thrust the 75 boss outwardly away from the chute. The set screw F¹², mounted in the machine frame serves to limit the outward travel of the yoke. The yoke F¹ is provided adjacent its pivot with an outward projection or bracket 80 G perforated as at G¹ and provided with a pin G² passing through the perforation and adapted to penetrate the upper end G³ of the pin G⁴, the lower end of which slidably engages or passes through a bracket G⁵ on the lever arm H later to be described. The upward movement of the pin G⁴ is limited by the stop screw F⁸ striking stop pin E²⁰ in plate E² of chute E¹. Surrounding the pin G⁴ is the spiral spring G⁷ adapted to be 85 compressed by the bracket G⁵ against the flange thus to lift the pin G⁴ and oscillate the yoke F¹.

H is a bell crank lever which carries the bracket G⁵ and is pivoted as at H¹ to the 90 frame of the machine. The bent continuation H² of the lever is provided with a cam roller H³ which is adapted to contact the cam C and be moved in response to the cam surface thereon. The outer end of the lever 100 H is slotted as at H⁴ to engage the pin H⁵ which projects outwardly through the slot H⁶ in the plates H⁷ secured to the machine frame by the bracket H¹⁰ the pin being connected to the punch element H⁸ which is 105 axially perforated in its upper end as at H⁹, to fit about the nail. The punch H⁸ is slidably confined between the edge of the bracket H¹⁰, the plates H⁷, and the block H¹², the upper end of which is engaged by 110 the lower end of the chute E.

When the lever H is in the position shown in Figure 3, the punch is withdrawn downwardly until the head lies beneath the outlet of the washer feed E. The upper plate or 115 top A of the machine is provided with a peripheral track A¹⁰ upon which the nail knob pairs ride. The nail knob pairs are carried about the peripheral track, by the carrier table A⁴ being contained in the notches A⁵ 120 therein, as shown in Figure 1. This track is slotted as at A¹² in line with the punch, the tip of the nail which has already been inserted through the knobs, riding within the slot. Overlying the punch is the nail 125 thrust bracket J secured at the top, as by the arm J¹ to any suitable frame member J². At its bottom it is secured to the top or frame of the machine, as by the pedestal J²⁰ and screws J²⁵ shown in Figure 2. The bracket 130

is axially perforated as at J^8 and slidably mounted in this perforation is the thrust stop or plug J^9 which is provided with a stem J^6 , slideable therein, extending up through the aperture J^8 , and centered by the plug member J^6 screw-threaded into the top of the bracket J .

The stem J^6 carries at its bottom the nail engaging head J^7 , and at its top, above the plug J^6 , a washer J^8 mounted on the reduced portion J^9 , which extends upwardly through the aperture J^{10} of the adjustable, screw-threaded cap J^{11} . J^9 is provided at its top with the check nuts J^{12} .

Compressed between the cap J^{11} and the washer J^8 is the light spiral spring K , and compressed between the plug J^6 and the stop J^9 is the heavy spiral spring K^1 .

I have described and shown a working device, but it will be realized that there can be many changes made in the size, shape, number and disposition of parts without departing from the spirit of my invention, and I wish the specification and drawings to be taken, therefore as in a large sense diagrammatic.

In particular the term perforated punch has been used in many of the claims. It will be understood that this term is not limited in its application to an axially perforated punch but is limited to cover any washer engaging element which is adapted to force the washer upon the shank of the nail.

The use and operation of my invention are as follows:

I illustrate a device for securing a nail knob assembly on a nail, by applying to the stem of the nail beneath the nail knobs, a single metal washer, the central perforation of which is of such diameter in relation to the stem of the nail as to permit its being forced upon the nail, without allowing ready removal as shown in Figure 10, the inner edge of the washer clamps or cuts into the nail. In the use of my invention I assemble the nail knobs and pass a nail through them and apply protecting washers above and below the knobs if so desired. These various steps are indicated only in outline so far as they are shown at 11, as they do not per se form a part of the present invention.

I then pass the nail knob assembly by the step by step rotation of the circular carrying table, illustrated for example in Figure 1, to the proper position on the machine above the punch and below the thrust bracket. I provide a feed hopper for the metal washers which is kept supplied with washers in any suitable way. The bottom of the hopper is slotted and in the slot oscillates a member which I call the hopper blade, the upper edge of which is provided with a slot of the proper width to hold the metal washers on edge, and carries a plu-

rality of wires which stir up the washers and feed them to the slot. The blade is carried by a lever pivoted adjacent the hopper.

The hopper blade is driven through the link D^1 from the gear B^2 and as the gear rotates the blade oscillates up and down. When in its lowest position, it merely closes the slot in the bottom of the hopper, but when in its highest position it feeds the washers inwardly along the small slot in the blade top which is then inclined downwardly toward the washer feed chute E . At the top of the chute E is a kick-out lever which, as elsewhere described, operates in response to the oscillation of the hopper blade lever, closing the top of the chute when the blade is withdrawn and leaving it free when the blade is in washer feeding position. If oversized or distorted washers enter the chute and become stuck, the effect of the spring K^1 which snaps down the rod K^2 is sufficient to give the kick-out member a sharp motion whereby the jammed washer is expelled into the hopper. The normal washers pass down the feed chute E , dropping to the elbow section E^1 . At this point, their passage is normally checked by the pin F^2 . This pin however, is controlled by a yoke which is oscillated back and forth in response to the lever H which in turn is controlled by the rotation of the cam C which rotates with the gear B^2 . This cam is provided with a gradually rising cam surface C^1 , and an abrupt descending surface C^2 and intervening broken or oscillating surface C^3 .

When the rising surface engages the roller H^1 on the lever H , the pin F^2 is lifted and the chute controlling pin F^2 is withdrawn to permit the washers to feed forward into contact with the pin F^2 . When the cam surface C^2 permits the lever H to drop, the pin F^2 is drawn back across the chute, but the pin F^2 is withdrawn and permits one washer to feed forward. The washers thus pass successively past the two pins and are dropped from the end of the chute section E^1 to the top of the punch H^2 . It receives the washers when in its lowest position, as shown in Figure 9. The washer is delivered edge-wise and is seated on the punch by the jiggling movement of the punch imparted to it through the lever H in response to the engagement of the roller H^1 with the scallops C^3 on the cam C . The jiggling motion caused by the engagement of the roller H^1 with the broken cam surface C^3 does not affect this feeding action since the flange G^1 is spaced sufficiently above the spiral spring G^2 to permit considerable play of the bracket without lifting G^1 .

The same cam action which controls the washer feed also controls the punch and as the lever H rises, it forces the punch upwardly against the nail, the point of the nail

- penetrating the upper axial aperture of the punch. Positioned on the top of the punch is the washer, the perforation of which overlies the perforation of the punch. The jiggling of the cam surface serves to oscillate the punch and place the washer into horizontal position, it being of course, fed to the punch on edge. Therefore, as the punch rises about the nail, it carries the washer with it, the washer aperture forming a tight fit, but not sufficiently tight to overcome the pressure of the spring K^1 . The nail is kept yieldingly in position by the nail engaging head J^1 which engages the head of the nail.
- 15 The spring K is compressed and as the check nut makes a normal movement with only about one-eighth inch it indicates that the punch is normally operating and that the washers are properly co-operating therewith.
- 20 If for any reason, the washer feed jams and no washers are fed forward the punch will pass about the nail and without lifting it, and the nuts J^{12} will not move above the cap J^{11} . If for any reason a washer without an aperture or with too tight an aperture is fed to the punch, the nail will of course be unable to penetrate the punch, and will be forced upwards through K and lifting the nuts K^{12} , and secondly compressing the head J^1 against the plug J^4 , compressing the spring K^1 to the full stroke of the punch.
- 25 Thus the machine automatically indicates the failure of the washer feed, by a want of any movement of the nuts J^{12} and the feed of a defective washer, by the abnormal movement of the nuts J^{12} and the stem on which they are mounted. Furthermore, the springs K K^1 automatically prevent any damage from such defective feed.
- 30 It will be understood that in the present specification and claims the term pair or pairs of nail knobs is used to denote an assembly comprising a pair of nail knob elements mounted on or to be mounted on a single nail. The completed knob commercially so called comprises a pair of nail knob elements mounted on a single nail and preferably held permanently in position on said nail.
- 35 I claim:
1. A machine for applying a metal washer to a nail knob assembly which consists in a nail knob feed and means for actuating it, a perforated punch adapted to surround the nail of said nail knob, means for actuating the punch to carry the metallic washer upon said nail, and means for feeding washers thereto, comprising a hopper, a washer chute, extending from said hopper to said punch, and means responsive to the movement of the punch for supplying washers to said chute, comprising a washer lifting blade adapted to be reciprocated from the bottom of said hopper to a point opposite
- 40 said chute, a plurality of agitating wires 65 mounted along the top of said blade.
2. A machine for applying a metal washer to a nail knob assembly which consists in a nail knob feed and means for actuating it, a perforated punch adapted to surround the nail of said nail knob, means for actuating the punch to carry the metallic washer upon said nail, and means for feeding washers thereto, comprising a hopper, a washer chute 70 extending from said hopper to said punch, and means responsive to the movement of the punch for supplying washers to said chute, comprising a washer lifting blade adapted to be reciprocated from the bottom of said hopper to a point opposite said chute, a plurality of agitating wires 75 mounted along the top of said blade, the top of said blade being slotted in line with said chute.
3. A machine for applying a metal washer 80 to a nail knob assembly which consists in a nail knob feed and means for actuating it, a perforated punch adapted to surround the nail of said nail knob, means for actuating the punch to carry the metallic washer upon said nail, means for feeding the metallic washer to said punch, comprising a washer chute and a supply source therefor, and means responsive to the reciprocation of the punch for permitting the washers to 85 feed down said chute, comprising a plurality of pins and means for inserting them across the path of the chute, from opposite sides, said pins being spaced apart, and means for reciprocating them in unison.
4. A machine for applying a metal washer 90 to a nail knob assembly which consists in a nail knob feed and means for actuating it, a perforated punch adapted to surround the nail of said nail knob, means for actuating the punch to carry the metallic washer upon said nail, means for feeding a metallic washer to said punch, comprising a washer chute and a supply source therefor, and means responsive to the reciprocation of the punch for permitting the washers to feed 95 down said chute comprising a plurality of pins and means for inserting them across the path of the chute, from opposite sides, the space between the pins being sufficient 100 to admit a washer therebetween.
5. A machine for applying a metal washer 105 to a nail knob assembly which consists in a nail knob feed and means for actuating it, a perforated punch adapted to surround the nail of said nail knob, means for actuating the punch to carry the metallic washer upon said nail, means for feeding a metallic washer to said punch, comprising a washer chute and a supply source therefor, and means responsive to the reciprocation of the punch for permitting the washers to feed 110 down said chute, comprising a plurality of pins and means for inserting them across the path of the chute, from opposite sides, the space between the pins being sufficient 115 to admit a washer therebetween.

pins and means for inserting them across the path of the chute, from opposite sides, and means for reciprocating said pins in unison, in response to the punch motion, the pins being spaced and proportioned to admit a washer therebetween at one excursion, and to discharge it to the punch at the next.

6. A machine for applying a metal washer to a nail knob assembly which consists in a nail knob feed and means for actuating it, a perforated punch adapted to surround the nail of said nail knob, means for feeding a metallic washer to said punch, means for actuating the punch to carry the metallic washer upon said nail, and means for preventing withdrawal of the nail during the punching operation comprising a stop plunger adapted to contact the head of the nail, a head at the lower end thereof, a secondary stop element slidable upon said plunger and adapted to be contacted by said head upon a brief upward excursion of the plunger, a supporting element in which the plunger and stop are mounted and a spring adapted to be compressed between said stop and said supporting element.

7. A machine for applying a metal washer to a nail knob assembly which consists in a nail knob feed and means for actuating it, a perforated punch adapted to surround the nail of said nail knob, means for feeding a metallic washer to said punch, means for actuating the punch to carry the metallic washer upon said nail, and means for preventing withdrawal of the nail during the punching operation comprising a stop plunger adapted to contact the head of the nail, a head at the lower end thereof, a stop element slidable upon said plunger and adapted to be contacted by said head upon a brief upward excursion of the plunger, a supporting element in which the plunger and stop are mounted and a spring adapted to be compressed between said stop and said supporting element, and an additional yielding means adapted to be compressed by the upward motion of the plunger prior to the compression of the first mentioned spring.

8. A machine for applying a metal washer to a nail knob assembly which consists in a nail knob feed and means for actuating it, a perforated punch adapted to surround the nail of said nail knob, means for feeding a metallic washer to said punch, means for actuating the punch to carry the metallic washer upon said nail, and means for preventing withdrawal of the nail during the punching operation comprising a stop plunger adapted to contact the head of the nail, a head at the lower end thereof, a stop element slidable upon said plunger and adapted to be contacted by said head upon a brief upward excursion of the plunger, a supporting element in which the plunger and stop are mounted and a spring

adapted to be compressed between said stop and said supporting element, the top of said plunger being provided with a movement indicating member projecting above the top of the supporting element.

9. A machine for applying a metal washer to a nail knob assembly which consists in a nail knob feed and means for actuating it, a perforated punch adapted to surround the nail of said nail knob, means for feeding a metallic washer to said punch, means for actuating the punch to carry the metallic washer upon said nail, and means for preventing withdrawal of the nail during the punching operation comprising a stop plunger adapted to contact the head of the nail, a head at the lower end thereof, a stop element slidable upon said plunger and adapted to be contacted by said head upon a brief upward excursion of the plunger, a supporting element in which the plunger and stop are mounted and a spring adapted to be compressed between said stop and said supporting element, and an additional yielding means adapted to be compressed by the upward motion of the plunger prior to the compression of the first mentioned spring, the top of said plunger being provided with a movement indicating member projecting above the top of the supporting element.

10. A machine for applying a metal washer to a nail knob assembly which consists in a nail knob feed and means for actuating it, a punch adapted to apply a metallic washer to the nail of said nail knob, a metallic washer feed and means for feeding washers thereto, and a controlling element adapted to control the passage of washers down said feed, and means for driving said punch and said control element in unison, comprising a cam, a punch actuating element driven thereby, and a connection between said element and the controlling element, said connection being responsive only to a predetermined minimum movement of the punch actuating element.

11. A machine for applying a metal washer to a nail knob assembly which consists in a nail knob feed and means for actuating it, a punch adapted to apply a metallic washer to the nail of said nail knob, a metallic washer feed and means for feeding washers thereto, and a controlling element adapted to control the passage of washers down said feed, and means for driving said punch and said control element in unison, comprising a punch actuating element and a connection between said element and the controlling element.

12. A machine for applying a metal washer to a nail knob assembly which consists in a nail knob feed and means for actuating it, a punch adapted to apply a metallic washer to the nail of said nail knob, a

- 6
13. A machine for applying a metal washer to a nail knob assembly which consists in a nail knob feed and means for actuating it, a punch adapted to apply a metallic washer to the nail of said nail knob, a metallic washer feed and means for feeding washers thereto, and a controlling element adapted to control the passage of washers down said feed, and means for driving said punch and said control element in unison, comprising a punch actuating element and a connection between said element and the controlling element, said connection being responsive only to a predetermined minimum movement of the punch actuating element.
14. A machine for applying a metal washer to a nail knob assembly which consists in a nail knob feed and means for actuating it, a punch adapted to apply a metallic washer to the nail of said nail knob, a metallic washer feed and means for feeding washers thereto, and a controlling element adapted to control the passage of washers down said feed, and means for feeding washers thereto, and unit means for reciprocating said punch and for jigging the punch to position on the washer thereupon.
15. A machine for applying a metal washer to a nail knob assembly which consists in a nail knob feed and means for actuating it, a punch adapted to apply a metallic washer to the nail of said nail knob, a metallic washer feed and means for feeding washers thereto, and a controlling element adapted to control the passage of washers down said feed, and means for feeding washers thereto and unit means for reciprocating said punch and for jigging the punch to position the washer thereupon, comprising a cam element having a continuous inclined cam surface, and a broken jiggling surface, and a punch driving element adapted to respond to said cam surfaces in succession.
16. A machine for applying a metal washer to a nail knob assembly which consists in a nail knob feed and means for actuating it, a punch adapted to apply a metallic washer to the nail of said nail knob, a metallic washer feed and means for feeding washers thereto, and a controlling element adapted to control the passage of washers down said feed, and means for feeding washers thereto, and unit means for reciprocating said punch and for jigging the punch to position the washer thereupon, comprising a cam element having a continuous, inclined cam surface, and a broken jiggling surface, and a punch driving element adapted to respond to said cam surfaces in succession, and a connection between said punch driving element and said control element, said connection being inoperative during the response of the punch driving element to said jiggling cam surface.
17. A machine for applying a metal washer to a nail knob assembly which consists in a nail knob feed and means for actuating it, a perforated punch adapted to surround the nail of said nail knob, means for actuating the punch to carry the metallic washer upon said nail, means for feeding the metallic washer to said punch, comprising a washer chute and a supply source therefor, and means responsive to the reciprocation of the punch for controlling the feed down said chute, comprising a plurality of pins adapted to penetrate said chute from opposite sides, and means for reciprocating them into and out of chute-closing position.
18. In a nail knob assembling and securing machine, means for conveying through said machine assembled pairs of nail knobs, having a nail positioned in their central apertures, a punch, means for feeding thin metallic washers thereto and means for actuating said punch to force said washers upon said nails.
19. In a nail knob assembling and securing machine, means for conveying through said machine assembled pairs of nail knobs, having a nail positioned in their central apertures, a punch aligned beneath said assembled nail knobs, means for feeding thin metallic washers to said punch and means for actuating said punch to force said washers up about said nails.
20. In a nail knob assembling and securing machine, means for conveying through said machine assembled pairs of nail knobs having nails positioned in their central apertures, a perforated punch adapted to surround the nail of each of said pairs of nail knobs, means for feeding metallic washers to said punch and means for actuating said punch to force the metallic washer upon said nail, the washer feeding means comprising a hopper, a washer chute extending from said hopper to said punch, a washer lifting segment adapted to be rotated about a center located beyond the wall of said hopper, and adapted to deliver washers to said chute.
21. In a nail knob assembling and securing machine, means for conveying through said machine assembled pairs of nail knobs having a nail positioned in the central aperture of each assembled pair of nail knobs, a punch, means for feeding thin metallic washers to said punch and means for actuating said punch to force said washers upon said nail, the washer feeding means comprising a washer chute adapted to hold the washers in vertical position during their passage therethrough, a washer hopper and

- means responsive to the reciprocation of the punch for delivering washers from said hopper to said chute.
22. In a nail knob assembling and securing machine, means for conveying through said machine assembled pairs of nail knobs having a nail positioned in the central aperture of each assembled pair of nail knobs, a punch, means for feeding thin metallic washers to said punch and means for actuating said punch to force said washers upon said nails, the washer feeding means comprising a washer chute adapted to hold the washers in vertical position during their passage therethrough, a washer hopper and means responsive to the reciprocation of the punch for delivering washers from said hopper to said chute, and means for horizontally positioning said washers upon said punch after their passage through said chute. 70
23. In a nail knob assembling and securing machine, means for conveying through said machine assembled pairs of nail knobs having a nail positioned in the central aperture of each assembled pair of nail knobs, a punch, means for feeding thin metallic washers to said punch and means for actuating said punch to force said washers upon said nails, the washer feeding means comprising a washer chute adapted to hold the washers in vertical position during their passage therethrough, a washer hopper and means responsive to the reciprocation of the punch for delivering washers from said hopper to said chute, and means for horizontally positioning said washers upon said punch after their passage through said chute comprising means for jiggling said punch prior to its excursion along the nail. 80
24. In a nail knob assembling and securing machine, means for conveying through said machine assembled pairs of nail knobs having a nail positioned in the central aperture of each assembled pair of nail knobs, a perforated punch aligned with the nail and adapted to surround it, means for feeding metallic washers to said punch, means for actuating the punch to force a metallic washer upon the nail and means for preventing the withdrawal of the nail during the travel of the punch comprising a stop plunger adapted to contact the head of the nail. 100
25. In a nail knob assembling and securing machine, means for conveying through said machine assembled pairs of nail knobs having a nail positioned in the central aperture of each assembled pair of nail knobs, a perforated punch aligned with the nail and adapted to surround it, means for feeding metallic washers to said punch, means for actuating the punch to force a metallic washer upon the nail and means for preventing the withdrawal of the nail during the travel of the punch, comprising a stop plunger adapted to contact the head of the nail. 110
26. In a nail knob assembling and securing machine, means for conveying through said machine assembled pairs of nail knobs having a nail positioned in the central aperture of each assembled pair of nail knobs, a perforated punch aligned with the nail and adapted to surround it, means for feeding metallic washers to said punch, means for actuating the punch to force a metallic washer upon the nail and means for preventing the withdrawal of the nail during the travel of the punch, comprising a stop plunger adapted to contact the head of the nail, an inclosing and aligning casing for said stop plunger, the outer end of said plunger projecting through the end of said casing to form an indicator element. 120
27. A machine for applying a metal washer to a nail knob assembly which consists in a nail knob feed and means for actuating it, a perforated punch adapted to surround the nail of said nail knob, means for feeding a metallic washer to said punch, means for actuating the punch to carry the metallic washer upon said nail, and means for preventing withdrawal of the nail during the punching operation comprising a stop plunger adapted to contact the head of the nail, a head at the lower end thereof, a secondary stop element slidable upon said plunger and adapted to be contacted by said head upon a brief upward excursion of the plunger, an inclosing and aligning casing in which the plunger and stop are mounted and a spring adapted to be compressed between said stop and said casing, the outer end of said plunger projecting through the end of said casing to form an indicator element. 130
28. In a nail knob assembling and securing machine, means for conveying through said machine assembled pairs of nail knobs having a nail positioned in the central aperture of each assembled pair of nail knobs, a punch aligned with the nail, means for feeding metallic washers to said punch, means for actuating the punch to force said washers upon said nail and means for preventing the withdrawal of the nail during the punching operation comprising a stop plunger adapted to contact the head of the nail, an aligning and inclosing casing therefor, a plurality of yielding means for resisting the movement of the nail in response to the actuation of the punch, the end of said stop plunger projecting through the end of said casing to form an indicator element. 140
29. A machine for applying a metal

washer to a nail knob assembly which consists in a nail knob feed and means for actuating it, a perforated punch adapted to surround the nail of said nail knob, a metallic washer feed chute, and means for feeding washers thereto, and a controlling element adapted to control the passage of washers down said feed comprising a pair of pins adapted to be reciprocated in unison through said chute, said pins penetrating said chute from opposite sides, and being so proportioned that when one pin penetrates the chute the other is out of line therewith.

15. 30. A machine for applying a metal washer to a nail knob assembly which consists in a nail knob feed and means for actuating it, a perforated punch adapted to surround the nail of said nail knob, a metallic washer feed chute, and means for feeding washers thereto, and a controlling element adapted to control the passage of washers down said feed comprising a pair of pins adapted to be reciprocated in unison through said chute, said pins penetrating said chute from opposite sides, and being so proportioned that when one pin penetrates the chute the other is out of line therewith, and means for driving said punch and said pins in fixed timed relation.

31. A machine for applying a metal washer to a nail knob assembly which consists in a nail knob feed and means for actuating it, a perforated punch adapted to surround the nail of said nail knob, a metallic washer feed chute, and means for feeding washers thereto, and a controlling element adapted to control the passage of washers down said feed comprising a pair of pins adapted to be reciprocated in unison through said chute, said pins penetrating said chute from opposite sides, and being so proportioned that when one pin penetrates the chute the other is out of line therewith, and means for driving said punch and said pins in fixed timed relation to permit the passage of one washer for each reciprocation of the punch.

32. A machine for applying a metal washer to a nail knob assembly which consists in a nail knob feed and means for

actuating it, a punch adapted to apply a metallic washer to the nail of said nail knob, a metallic washer feed adapted to convey the washer along a vertical plane, and means for feeding washers thereto, a controlling element adapted to control the passage of washers down said feed, and unit means for reciprocating said punch and for jiggling the punch to position the washer thereupon.

33. In a nail knob assembling and securing machine, means for conveying through said machine assembled pairs of nail knobs having a nail positioned in the central aperture of each assembled pair of nail knobs, a punch aligned with said nails, means for feeding metallic washers thereto, means for actuating the punch to force a washer upon each nail and feeding means for said punch comprising a downwardly inclined chute adapted to convey washers along a vertical plane, a hopper adjacent the upper end of said chute, a washer gathering segment-shaped blade mounted to rotate about a center removed from said hopper and adapted to be rotated from the bottom of the hopper to a point in line with said chute, the top of said blade being slotted.

34. In a nail knob assembling and securing machine, means for conveying through said machine assembled pairs of nail knobs having a nail positioned in the central aperture of each assembled pair of nail knobs, a punch aligned with said nails, means for feeding metallic washers thereto, means for actuating the punch to force a washer upon each nail and feeding means for said punch comprising a downwardly inclined chute adapted to convey washers along a vertical plane, a hopper adjacent the upper end of said chute, a washer gathering segment-shaped blade mounted to rotate about a center removed from said hopper and adapted to be rotated from the bottom of the hopper to a point in line with said chute, the top of said blade being slotted, and guide wires extending along said slot.

Signed at Cleveland county of Cuyahoga and State of Ohio, this 9th day of October, 1922.

FRANCIS M. CASE.
